US0D1065511S

(12) **United States Design Patent** (10) **Patent No.:** **US D1,065,511 S**
(45) **Date of Patent:** **** Mar. 4, 2025**

(54) **PATIENT INTERFACE COVER**

(71) Applicant: **Fisher & Paykel Healthcare Limited**,
Auckland (NZ)

(72) Inventors: **Silas Sao Jin Siew**, Auckland (NZ);
Wen Dong Huang, Auckland (NZ);
Craig Robert Prentice, Auckland (NZ);
Andrew Paul Maxwell Salmon,
Auckland (NZ)

(73) Assignee: **Fisher & Paykel Healthcare Limited**,
Auckland (NZ)

(**) Term: **15 Years**

(21) Appl. No.: **29/920,088**

(22) Filed: **Dec. 7, 2023**

Related U.S. Application Data

(60) Division of application No. 29/868,936, filed on Dec. 16, 2022, now Pat. No. Des. 1,013,861, which is a division of application No. 29/695,067, filed on Jun. 14, 2019, now Pat. No. Des. 977,087, which is a continuation of application No. 29/616,082, filed on Sep. 1, 2017, now Pat. No. Des. 857,190, which is a continuation of application No. 29/541,452, filed on Oct. 2, 2015, now Pat. No. Des. 798,439, which is a continuation of application No. 29/469,110, filed on Oct. 7, 2013, now Pat. No. Des. 740,409, which is a continuation of application No. 29/368,392, filed on Aug. 23, 2010, now Pat. No. Des. 691,257.

(57) **CLAIM**

The ornamental design for a patient interface cover as shown and described.

DESCRIPTION

FIG. 1 is a top plan view of a cover of a frame assembly of a patient interface cover;

FIG. 2 is a front elevational view of the cover of FIG. 1;

FIG. 3 is a perspective of the cover of FIG. 1;

FIG. 4 is a right side elevational view of the cover of FIG. 1;

FIG. 5 is an alternate perspective view of the cover of FIG. 1; and,

FIG. 6 is a rear elevational view of the cover of FIG. 1.

1 Claim, 3 Drawing Sheets
